SEPARATION OF AROMATIC HYDROCARBONS FROM NON-AROMATIC HYDROCARBONS UTILIZING A LACTAM-WATER SOLVENT

Richard D. Morin, John B. Fishel, and Arthur E. Bearse, Columbus, Ohio, assignors, by mesne assignments, to The Ohio Oil Company, Littleton, Colo., a corporation of Ohio

Application December 6, 1954, Serial No. 473,378

8 Claims. (Cl. 208—324)

This invention relates to the separation of hydrocarbon mixtures. In particular, this invention is concerned with the separation of aromatic hydrocarbons from nonaromatic hydrocarbons. By aromatic hydrocarbons are meant those hydrocarbons which contain one or more benzene rings or related condensed aromatic rings such as naphthalene, phenanthrene, anthracene, acenaphthene, etc., and alkylated and alkenylated derivatives of these. Nonaromatic hydrocarbons include the acyclic and alicyclic, saturated and unsaturated hydrocarbons.

Separation of these two classes of hydrocarbons has become of increasing importance industrially, and many methods have been proposed for the separation of aromatic from nonaromatic hydrocarbons. The complex mixtures of hydrocarbons which occur naturally in petroleum or those obtained from various refinery processing steps often contain mixtures of aromatic and nonaromatic hydrocarbons which are difficultly separable from each other, if at all, by fractional distillation methods. Selective solvent extraction, selective adsorption on solid adsorbents such as silica gel, and extractive distillation have been used with varying degrees of success. In the selective solvent method, a solvent must preferentially dissolve the aromatic hydrocarbons to form a separable extract phase richer in aromatic hydrocarbons and a raffinate poorer in aromatic hydrocarbons than the original hydrocarbon mixture. A good selective solvent should show a high degree of selectivity for aromatic hydrocarbons, should have a low solubility in the raffinate, should be readily separable from the aromatic hydrocarbons in the extract phase, should be easily recoverable, and should be stable to allow recycling. Solvents which have been used for selective extraction of aromatic hydrocarbons from mixtures with other hydrocarbons include sulfur dioxide, furfural, diethylene glycol, polyethylene glycols, dimethyl formamide, oxydipropionitrile, thiadipropionitrile, etc. These solvents are not entirely suitable in all respects because of either one or more disadvantages due to poor selectivity, high solubility in the raffinate, difficulties in recovery, or instability in subsequent recycling.

The object of this invention is the separation of aromatic hydrocarbons from nonaromatic hydrocarbons by means of a selective solvent. A further object is to provide a method for obtaining aromatic hydrocarbons substantially free from nonaromatic hydrocarbons by means of an effective selective solvent. Still another object is to provide a cyclic process wherein the selective solvent can be easily recovered and reused in the process.

The objects of this invention are accomplished by extraction of the mixture of aromatic and nonaromatic hydrocarbons with a solvent selected from the class of cyclic inner amides of gamma-amino acids, commonly known as gamma-lactams. The gamma-lactams preferred for purposes of this invention are the alkyl substituted lactams of gamma-aminobutyric acid and gamma-aminobutyric

2

butyric acid. These gamma-lactams may be represented by the structural formula

wherein the gamma-butyrolactam skeletal nucleus

may be either saturated or unsaturated and wherein R₁ is either hydrogen or short-chain alkyl groups and R₂ is a short chain alkyl group. It is to be understood that R₁ may represent more than one short-chain alkyl group attached to a substitutable carbon atom in the gamma-butyrolactam skeletal nucleus. The substitution of alkyl groups in the gamma-butyrolactam nucleus decreases the selective efficiency of the compound, that is, selective efficiency of the solvents of this invention decreases as the length of the carbon chain of the alkyl group increases. By selective efficiency is meant the ability of the solvent to extract the aromatic hydrocarbons in preference to nonaromatic hydrocarbons and the ability to form discrete phases as a means of obtaining the desired separation.

In practice, the hydrocarbon mixture containing aromatic and nonaromatic hydrocarbons is admixed thoroughly with the selective solvent selected from the aforementioned class of compounds by any suitable means, such as mechanical agitation or in a countercurrent extraction column, and a small amount of water sufficient to compensate for the decreased selective efficiency is added either to the solvent or the solvent-hydrocarbon mixture. Two immiscible phases are formed which are separated. The upper phase or raffinate has an appreciably lower content of aromatic hydrocarbons than the original mixture and contains a small amount of selective solvent. The raffinate may be washed with water to remove the small amount of solvent dissolved therein. The lower extract phase is composed of a solution of aromatic hydrocarbons in the selective solvent. By the choice of proper solvents in the class defined, and by regulation of conditions such as temperatures, ratio of selective solvent to the original hydrocarbon mixture, and water content of the selective solvent, varying amounts of the aromatic hydrocarbons originally present can be removed. Thus, it is possible to obtain raffinates which are substantially free of aromatic hydrocarbons and extract phases which contain virtually all of the aromatic hydrocarbons of the original mixture. It is also possible to vary the amount of the aromatic hydrocarbon in the extract phase, depending upon the gamma-lactam used, and by proper control of temperature, solvent-hydrocarbon ratio, and water content in the solvent.

One of the outstanding features of the selective solvents of this invention is their ease of removal from hydrocarbons by water washing. To recover the aromatic hydrocarbons, the extract phase is contacted and washed with water. The selective solvent separates with the water as an aqueous solution immiscible with the aromatic hydrocarbon fraction. Phase separation may be facilitated by dilution with a low-density hydrocarbon or mixture of hydrocarbons. The aromatic fraction, after distilling off the diluent, may, if desired, be further processed by distillation, but is suitable for many uses without further treatment. Recovery of the selective solvent from the aqueous phase solution is effected by distillation which gives an aqueous distillate and a residue of solvent. The recovered solvent then may be reused to treat more of the hydrocarbon mixture.

Solvents in the class defined above are stable under the conditions of the extraction and recovery process, and have been recycled without evidence of deterioration. The only additional solvent needed is to make up any operating losses.

The drawing is a diagrammatic representation of a cyclic process using the selective solvents of the present invention in a continuous process for the separation of hydrocarbon mixtures. The arrows in the diagram indicate the direction of flow. The drawing is described with reference to gamma-butyrolactam extraction of light catalytic cycle oil, a refinery product comprising aromatic hydrocarbons and non-aromatic hydrocarbons in the boiling range of 400° to 600° F. The butyrolactam from storage tank 1 is admitted through line 2 to the top of countercurrent extraction column 3. Light catalytic cycle oil from storage tank 4 is fed through line 5 to the bottom of the column 3. The ratio of the butyrolactam to hydrocarbon mixture is maintained at the desired level by controlling the flow rates of the two liquids. In extraction column 3, intimate contact of the butyrolactam with the light catalytic cycle oil is attained and the raffinate and extract phases are formed and separated. The raffinate rises to the top and passes through line 6 to the bottom of countercurrent extraction column 7. Water is admitted to the top of column 7 through line 8, and any butyrolactam carried over in the raffinate is removed as a dilute aqueous solution which leaves the bottom of column 7 through line 9. The washed raffinate passes through line 10 to raffinate storage tank 11. If desired, the washed raffinate may be subjected to further extraction with the gamma-lactams. Also, all or portions of the washed raffinate may be fed back or recycled to the extraction column 3 to obtain further extraction of any aromatic hydrocarbons remaining in the raffinate.

The extract phase from the bottom of column 3 passes through line 12 to the lower end of countercurrent extraction column 13 where it is contacted and washed with water to separate the butyrolactam from the aromatic hydrocarbon fraction. The latter fraction passes from the top of column 13 through line 14 to the aromatic hydrocarbon storage tank 15. If desired, a relatively low boiling, low-density diluent, such as hexane or gasoline, may be introduced into column 13, along with the extract, to lower the density of the aromatic hydrocarbon fraction and permit easier separation from the aqueous butyrolactam phase. This diluent subsequently may be removed from the higher boiling aromatic hydrocarbons by fractional distillation.

The aqueous solution of the butyrolactam obtained from the extract phase is fed from the bottom of column 13 through line 16 to the distillation tower 17. Aqueous butyrolactam from the bottom of column 7 is also fed to tower 17 through line 9. Distillation of the aqueous butyrolactam gives water as the overhead fraction which is condensed in condenser 18 and then used to wash the extract phase by passage through line 19 to the top of column 13; part of this distillate is used to wash the raffinate by passage through line 20 to the top of column 7. The high-boiling residue from the distillation of the aqueous butyrolactam is substantially pure butyrolactam suitable for reuse. The recovered butyrolactam is removed from the bottom of tower 17 and is returned through line 21 to the butyrolactam storage tank 1.

The separation of aromatic hydrocarbons from non-aromatic hydrocarbons by the selective solvents of this invention may be performed over a range of temperatures, the maximum operable temperature being that temperature at which two discrete phases continue to form. As the temperature increases, the phase separation becomes less discrete until the solubility of the solvent in hydrocarbon mixture is too high and immiscible phases are not obtained. The process usually is carried out at ambient room temperatures, although other temperatures may be preferred in processing certain mate-

rials in order to decrease viscosities and to facilitate phase disengagement.

The following examples are illustrative of the invention and are not intended as limitations thereof.

Example I

Twenty-five milliliters of light catalytic cycle oil containing about 25 percent, by weight, aromatic hydrocarbons was mixed with 25 milliliters of N-methyl-gamma-butyrolactam containing 5 percent, by weight, of water. Upon standing, two immiscible phases separated and the lower-extract phase was drawn off. This lower extract phase was mixed with an equal volume of water to liberate the aromatic hydrocarbons from the solvent. The aromatic hydrocarbon fraction was separated and washed with water to remove residual solvent and dried. This aromatic hydrocarbon fraction amounted to about 28 percent, by weight, of the original light catalytic cycle oil, and was substantially enriched in aromatic hydrocarbon content, as indicated by the refractive index (n_D^{25}) of 1.5691.

At ambient room temperature, the N-ethyl-gamma-butyrolactam was ineffective for the separation of an enriched aromatic hydrocarbon fraction from light catalytic cycle oil. It is believed that the ineffectiveness is due to the presence of the ethyl group in the gamma-butyrolactam skeletal nucleus. However, whatever the cause may be, it has been found that the addition of a small amount of water to the alkylated gamma-butyrolactams results in an effective means for extracting aromatic hydrocarbons from a mixture of aromatic and nonaromatic hydrocarbons. This is further illustrated in the following example:

Example II

Twenty-five milliliters of N-ethyl-gamma-butyrolactam containing 10 percent, by weight, of water was mixed with 25 milliliters of light catalytic cycle oil. On standing, two phases separated, and the lower extract phase was withdrawn. This extract phase was mixed with an equal volume of water to liberate the aromatic hydrocarbon fraction which separated. The aromatic hydrocarbon fraction was washed with water to remove residual solvent and then dried. This aromatic hydrocarbon fraction amounted to about 20 percent of the original light catalytic cycle oil. It had a refractive index (n_D^{25}) of 1.5762 and represented a product which was enriched in aromatic hydrocarbon content, as compared to the original cycle oil.

These examples illustrate that the separation of the extract phase from the raffinate becomes less discrete and the selective preference for aromatics over nonaromatics progressively decreases as the number of carbon atoms of the short-chain alkyl groups in the gamma-lactam nucleus increases. It is preferred that the amount of water used in the extraction step is in the order of about 10 percent, by weight, based on the weight of the gamma-lactam. However, the small amount of water necessary for extraction by the alkylated gamma-butyrolactam may be varied, depending upon the number of carbon atoms in the alkyl group. Although this invention is particularly useful for the separation of aromatic hydrocarbons from light catalytic cycle oil, it is contemplated that the invention may be used in the extraction of other mixtures of aromatic and nonaromatic hydrocarbons. Obviously, there may be many manipulative modifications and variations of the extractive processes in the use of this invention.

What is claimed is:

1. The process of obtaining an extract rich in aromatic hydrocarbons from a mixture of aromatic and nonaromatic hydrocarbons by means of phase separation comprising extracting said mixture with a selective solvent comprising N-methyl-gamma-butyrolactam and from 5 to 10 by weight of water.

2. The process of obtaining an extract rich in aromatic hydrocarbons from a mixture of aromatic and nonaromatic hydrocarbons by means of phase separation comprising extracting said mixture with a selective solvent comprising N-ethyl-gamma-butyrolactam and from 5 to 10% by weight of water.

3. The process of obtaining an extract rich in aromatic hydrocarbons from light catalytic cycle oil containing hydrocarbons having boiling points in the range of about 400° to about 600° F. comprising extracting said oil with a selective solvent comprising N-methyl-gamma-butyrolactam and from 5 to 10% by weight of water.

4. The process of obtaining an extract rich in aromatic hydrocarbons from light catalytic cycle oil containing hydrocarbons having boiling points in the range of about 400° to about 600° F. comprising extracting said oil with a selective solvent comprising N-ethyl-gamma-butyrolactam and from 5 to 10% by weight of water.

5. The process of obtaining an extract rich in aromatic hydrocarbons from a mixture of aromatic and nonaromatic hydrocarbons by means of phase separation comprising extracting said mixture with an N-alkyl-gamma-butyrolactam wherein said alkyl is a short-chain alkyl group wherein the number of carbon atoms is less than that which renders the lactam in the presence of small amounts of water nonselective for the aromatic hydrocarbons and from 5 to 10% by weight of water.

6. The process of obtaining an extract rich in aromatic hydrocarbons from a mixture of aromatic and nonaromatic hydrocarbons by means of phase separation comprising extracting said mixture with a selective solvent comprising from 5 to 10% by weight of water and at least one gamma-lactam represented by the structural formula

wherein R₁ is selected from the class consisting of hydrogen and a short-chain alkyl group and R₂ is a short-

chain alkyl group, the total number of carbon atoms in both of said alkyl groups being less than that which renders the lactam in the presence of small amounts of water nonselective for the aromatic hydrocarbons.

7. The process of obtaining an extract rich in aromatic hydrocarbons from a mixture of aromatic and nonaromatic hydrocarbons by means of phase separation comprising extracting said mixture with a selective solvent comprising from 5 to 10% by weight of water and a short-chain alkyl substituted, N-ethyl-gamma-butyrolactam, the number of carbon atoms in the short-chain alkyl substituent being less than that which renders the lactam in the presence of small amounts of water nonselective for the aromatic hydrocarbons.

8. The process of obtaining an extract rich in aromatic hydrocarbons from a mixture of aromatic and nonaromatic hydrocarbons by means of phase separation, comprising: adding N-ethyl-gamma-butyrolactam to said mixture whereby a miscible solution of the butyrolactam and the mixture is obtained; adding from 5 to 10% by weight of water to cause two phases to separate, one of said phases being an aqueous lactam phase containing an enriched extract of aromatic hydrocarbons.
